STIPPLE PAINT BRUSH

Jeston P. McManners, Houston, Tex.
(P.O. Box 988, Trinity, Tex. 75862)

Filed Feb. 10, 1969, Ser. No. 15,701

Term of patent 7 years

Int. Cl. D4—04

U.S. Cl. D4—38

Fig. 3

FIG. 1 is a top perspective view of a stipple paint brush showing my new design;

FIG. 2 is a bottom perspective thereof; and

FIG. 3 is a plan view as seen from the top of FIG. 2.

I claim:

The ornamental design for a stipple paint brush, as shown.
